CORRECT POSTURE SEAT FOR TOILET BOWLS

Stephen J. Thomas, Bellflower, Calif.

Application February 24, 1949, Serial No. 1,071

Term of patent 14 years

(Cl. D4—5)

To all whom it may concern:

Be it known that I, Stephen J. Thomas, a citizen of the United States of America, residing at Bellflower, county of Los Angeles, and State of California, have invented a new, original, and ornamental Design for Correct Posture Seat for Toilet Bowls, of which the following is a specification, reference being had to the accompanying drawing, forming a part thereof wherein:

Figure 1 is a perspective view of a correct posture seat for toilet bowls, showing my new design, and

The broken line showing of the toilet seat cover and flush tank is for illustrative purposes only.

I claim:

The ornamental design for a correct posture seat for toilet bowls, as shown and described.

STEPHEN J. THOMAS.
